UNITED STATES PATENT OFFICE.

FREDERICK HEATH, OF TACOMA, WASHINGTON, ASSIGNOR TO HEATH UNIT TILE COMPANY, OF TACOMA, WASHINGTON, A CORPORATION OF WASHINGTON.

SILO.

Application filed October 8, 1921. Serial No. 506,233.

To all whom it may concern:

Be it known that I, FREDERICK HEATH, a citizen of the United States, residing at Tacoma, in the county of Pierce and State 5 of Washington, have invented a certain new and useful Improvement in Silos, of which the following is a full, clear, and exact description, reference being had to the accompanying drawings.

10 This invention is directed to improvements in silos and is particularly concerned with that type of structure wherein the walls are of hollow masonry.

In building such silos, the general practice 15 has been to construct the circumferential wall of hollow concrete blocks or interlocking tile of various shapes and forms, the wall being reinforced by circular rods placed in the mortar beds. Considerable skill and 20 an undue amount of time is required, however, on the part of the builders to properly assemble the rods in the mortar beds, as the rods frequently are distorted in such a manner that they tend to displace the blocks before they are firmly set in the mortar bed. 25 Some forms of such tile blocks are adapted to have the rods laid in suitable grooves formed therein. Various expedients to overcome these and similar difficulties have been 30 tried but such expedients have been both inefficient and expensive.

The general object of the present invention therefore is to provide a simple and effective silo hollow wall construction where- 35 by such difficulties of building are eliminated and which is adaptable to a variety of architectural designs in which very marked economies are effected. In accom- 40 plishing the above objects I prefer to use hollow tile laid on reinforced horizontal mortar beds; the reinforcement being in the nature of short metal grids or sheets laid in the mortar beds in overlapping and bond- 45 ing relation as the successive courses of tile are set.

A more specific object of my invention is the provision of a silo construction wherein an outer circumferential wall may present an uninterrupted symmetrical and ar- 50 chitectural appearance, while an inner wall, which is bonded with the outer wall may contain the usual elongated filling opening or series of doors, and may serve as a partition forming a space between the walls

constituting the chute for filling and empty- 55 ing the silo. To provide an entrance to this chute, a comparatively small door at the ground level opens through the outer wall, wherefore the inner wall is reinforced and constitutes a chordal continuation of the cir- 60 umferential reinforcement opposite this door.

Other objects will be hereinafter set forth in connection with the following descrip- 65 tion which refers to the accompanying drawings and the essential characteristics will be summarized in the claims.

In Fig. 1 I have illustrated the general appearance of a silo wherein my construction is embodied; Fig. 2 is an enlarged cross- 70 sectional elevation showing the foundation of the silo and a part of the inner and outer wall; Fig. 3 is a section taken in the same plane as Fig. 2 showing the double wall or 75 chute construction at the top of the silo; Fig. 4 is a cross section taken through the door and the walls of the silo substantially along line 4—4 of Fig. 1; Fig. 5 is a plan view of the silo with the roof removed while 80 Fig. 6 is a sectional plan view similar to Fig. 4 but taken through the silo walls above the outer door head. Fig. 7 is an enlarged view of the three-void block.

As shown in the drawings I build my silo with an uninterrupted outer wall having 85 only a small door opening at the base. This outer wall may be constructed of voided blocks 1, short enough that it is not necessary to curve them.

Such a block is illustrated in Fig. 8. The 90 webs and shells of this block are so pro- portioned as to resist the vertical strains and preferably to develop the full strength 95 of the mortar bed. The individual blocks when in the wall must resist lateral strains due principally to the outward pressure of 100 the contents; therefore, the blocks are perfectly scored providing ribs and grooves indicated at 2 and 3 in Fig. 8. For convenience of illustration, these ribs and grooves are omitted in the smaller scale drawings of 105 the other figures. This block is particularly adaptable for constructing the wall of the silo as the voids 8 present annular insulating spaces extending about the circumfer- ence of the wall, which spaces are sealed in the ordinary mortar bonding of the blocks.

The circumferential stresses on the wall

which it is customary to resist by hoops, circumferential rods and the like, are taken care of in my construction by a novel, simple and effective means in the nature of narrow straight strips, short enough to lie within the inner and outer peripheries of the wall and laid with the ends overlapping and locked together by mortar filling the interstices thereof as well as by actual engagement of one with the other.

The circumferential reenforcement is illustrated particularly in Fig. 6. The sheets or strips 9 are preferably of a suitable expanded metal forming ribs which lie within the mortar bed as shown. The placing of these strips in the mortar bed involves no expert skill on the part of the mason as the mortar may be spread a sufficient distance over the preceding course to permit the laying of two or more strips with the ends thereof overlapping to insure a continuous circumferential bonding of the mortar beds. It will be noted that in such a wall construction the blocks in the outer wall serve merely to support the vertical load while the reinforced mortar beds serve to resist the circumferential stresses exerted upon the wall by the contents of the silo.

The chute is arranged within the outer circumferential wall of the silo and may be formed by an inner straight wall 10 constructed of single void blocks 11 which are approximately half the width of the three void blocks in the outer wall. This wall extends across the interior of the silo and diagrammatically is in the nature of a chord of a circle, the outer wall representing the circle. The usual filling opening is provided in the center of the wall, the opening being sealed by removable doors hereinafter described.

As this divided wall would not have sufficient strength to withstand the pressure of the contents of the silo, transverse reinforcing walls 15 and 16, constituting struts, serve to transmit the load exerted on the inner wall to the outer reinforced wall.

Since the reinforcing characteristics of the expanded metal strips cannot be obtained in the first ten mortar beds of the outer wall due to the formation of the outer door opening 28, it is important that the lower part of the inner wall be of such construction that the circumferential strength of these first ten mortar beds be maintained. Hence by constructing the lower portion of the inner wall of the three void tile, as illustrated in Fig. 2, it is possible to reinforce the mortar beds with expanded metal strings which may bond into the outer wall mortar beds. Hence the reinforced inner wall mortar beds are in the nature of the chordal continuations of the outer wall mortar beds. This inner double wall construction may extend a few courses above the outer door

opening and thereafter be formed of single void tile set in ordinary mortar beds. A manhole 22 may be formed at the base of the inner wall to permit access to the silage chamber.

The reinforcement may be placed in all of the lower mortar beds, of both the inner and outer wall, then in every second, third or fourth successive course of the outer wall since the circumferential stresses progressively decrease as the top of the structure is approached.

The filling may be formed in the single wall portion of the partition wall and may extend from the double wall construction to the full height of the structure. The sides of the door opening may be formed by a special hollow jamb tile having vertical voids and which may be of such dimensions that an efficient bonding of the jamb tile may be obtained. This block may be comprised of a seven void tile 25 which can be set in alternate courses; the bond being formed in the intermediate courses by the overlapping of the single void tile, a portion of the special tile being broken away by the mason to provide for this overlapping as illustrated by the block 24. Since the voids of this tile are vertical it may be used as a closure in constructing the transverse walls 15, and 16 as illustrated at 26; the recessed or jamb portion being broken off. Removable doors 30 may be of a double matched board construction with suitable insulating material, such as tar paper, therebetween. Guide strips 34 may be placed on the outer surface of the door which may abut the ends of the jamb tiles. Incidentally the transverse walls constitute two sides of the chute. The outer extremities of all of the inner walls may be bonded into the outer wall as illustrated at 17, 18 and 19; each alternate course of blocks having this inter-bonding relation with the outer wall. A single void block 20 may be used in the corresponding course of the outer wall where the inner walls are bonded therewith. The final top course of the outer wall may be comprised of a special hollow tile 37 preferably terra cotta with uniform serrations 38 formed at the outer edges for architectural effect. Any hollow tile however, of sufficient width to provide a proper bearing surface for the roof structure may be used.

The removable doors for sealing the elongated door opening in the inner wall may be of any height, but for convenience in handling, should not be more than three feet. Cross bars 35 and eccentric clamps 36 serve to lock the doors in place.

A very durable ladder may be provided in the chute when the walls are being constructed which is comprised of metallic tubes 38 having the ends thereof flattened and imbedded in every fourth course of the inner

and outer walls. A window 40 may be provided in the outer wall at the top of the chute to permit ventilation into the chute.

The roof may preferably be constructed of 5 concrete in the shape of a canopy or lid which may rest upon the crowning course of the outer wall. The roof may have suitable windows 41 to permit the passage of light into the silage chamber.

- 10 A special jamb tile may be used to form the outer door opening in the wall which may have the same interbonding characteristics as the narrower jamb tile used in forming the elongated door opening in the 15 inner wall. This same tile may be used in forming the door jambs of the manhole 22. Hence the manhole may be sealed by a suitable door 27^a which may be locked in place by cross bar 27^c and eccentric bolt 20 27^d. The cross bar may rest on anchor bands 27^e which may be placed in the mortar beds when the wall is being constructed. The outer door 28 may be of heavy construction somewhat in the nature 25 of a refrigerator door with suitable insulation 28^a inserted between the inner and outer door boards. The door may be supported on hinges 28^b which may be retained in place by suitable bolts laid in the horizontal 30 mortar beds of the outer wall. A cam latch 28^c serves to maintain the door in contact with the surfaces of the jamb tile with sufficient pressure to prevent any substantial leakage of air into the bottom of 35 the silo.

Silage is frequently lost due to freezing on the top or it may dry out to a depth of two or three feet. To prevent this waste I use a cover which may be comprised of a 40 canvas tarpaulin supported by an angular hoop 42 of sufficient dimensions to be conveniently raised and lowered within the silage chamber by cables 43 and 44. These cables may be suspended in proper position 45 by suitable sheave members 45 carried by a block 46 secured to the roof. The lower ends of the cables may be secured to counter weights 48 and 49 suspended within the enclosed spaces 50 and 51. The combined 50 weight of these counter weights may be equal to the weight of the covering device so that a slight pull exerted on an operating cable which passes up and down both sides of the wall 15, will cause the cover to be lowered and a paying out of this cable will cause the cover to be raised. A suitable 55 aperture 56 formed in the tarpaulin may be covered by a flap 57. Hence the flap may be folded back to permit light to pass into 60 the silage chamber.

The base or foundation of the silo may be of the usual concrete formation 9 having a bowl 9^a which constitutes the bottom of the silage chamber. The foundation walls may 65 have annular reenforcing rods 10^a positioned

therein and near the outer perimeter thereof. An outlet 9^b positioned in the bottom of the bowl serves as a drain for drippage and moisture settling from the silage.

From the foregoing description of my 70 silo construction, it is evident that no projections, edges, or corners are present in the silage chamber. Hence when the walls of the chamber are coated with cement or water-proofing material, smooth surfaces 75 are presented which may be readily cleaned before each refilling. Likewise, it is evident that the walls of the chute have no projections which would intercept or catch any of the silage as the same is thrown through 80 the door and dropped down the chute to the outer door. The base of the chute may be tapered slightly outwardly to permit the easy removal of any droppings or spilt silage. Furthermore, in my silo it is quite 85 convenient to place a small truck at the bottom of the chute into which the contents of the silo may be directly loaded.

The structure presents a symmetrical outer appearance and the construction of 90 the walls is such that architectural variations may be made without depreciating from the reenforcing characteristics thereof. Furthermore, it is quite apparent that the structure may be efficiently constructed by 95 any mason of ordinary skill; there being no dove tailed tile or interlocked bars, no lateral or vertical reenforcing rods and no curved blocks present in the structure.

Having thus described my invention, I 100 claim:—

1. A silo having an outer symmetrical wall composed of hollow blocks rectangular in cross section and reenforced horizontal mortar beds, the reinforcement comprising 105 expanded metal sheets laid in the mortar beds in overlapping relation, the vertical mortar bonds in each course of tile being such that uninterrupted, annular insulating spaces are present in the wall. 110

2. In a silo, an outer symmetrical wall composed of hollow blocks in horizontal courses separated by horizontal mortar beds, and reenforcing means in said mortar beds consisting of flat grid like strips overlapping 115 at their ends.

3. A silo having an outer wall constructed of hollow blocks and an inner wall extending across one side thereof in the nature of a chord of a circle, said inner wall having 120 an elongated door opening formed therein, the outer wall having an opening in alignment with said inner wall door opening and positioned below the bottom of said inner door opening. 125

4. In a silo structure, the combination of an outer circular wall formed of courses of hollow blocks set on mortar beds having overlapping sheet metal reenforcements, an inner wall having an elongated opening 120

therein and transverse walls having horizontal beds lying in the same plane as the mortar beds of the inner and outer wall; the alternate courses of said transverse walls being interbonded with the alternate courses of the inner and outer wall.

5. In a silo structure, the combination of an outer circular wall formed of courses of voided tile, mortar beds having overlapping metal gridlike reinforcements, an inner wall having an elongated opening therein and transverse walls having horizontal courses of blocks between the same planes as those of the inner and outer wall, said transverse walls being interbonded with the inner and outer wall.

6. A silo structure wherein there is an outer annular wall and an inner wall, the outer wall being constructed of hollow blocks and horizontal mortar beds having a circumferential reinforcement comprised of overlapping grid like metal sheets.

7. A silo structure wherein there is an outer circular wall and an inner straight wall bonded into the outer wall and dividing the inside of the structure into large and small vertical compartments, said wall having an elongated door establishing communication between said compartments throughout substantially the height of the compartments, the large compartment comprising a silage chamber, while the other provides a chute for loading the silage chamber, the inner wall being positioned to form obtuse angles at the inner side with the outer wall.

8. A silo structure wherein there is an outer circular wall and an inner wall dividing the interior of the structure into a silage chamber and chute chamber, the outer wall having a door opening at the base thereof and communicating with the chute chamber and the inner wall having an elongated door opening extending from above the first named door opening to substantially the top of the inner wall.

9. A silo structure having an outer circular wall composed of hollow blocks laid on reinforced horizontal mortar beds the continuity of the lower courses being broken by a door opening, an inner wall dividing the interior of the structure into two chambers and having the continuity of the upper courses broken by an elongated door opening, the mortar beds of the outer broken courses being bonded with the mortar beds of the unbroken courses of the inner wall by expanded metal sheets laid in overlapping relation in the mortar beds of said inner and outer courses.

10. A silo construction consisting of a symmetrical outer wall and an inner chordal wall connected therewith, there being a door opening through the outer wall and a filling opening through the inner wall, and a circumferential reinforcement for the silo extending across the chordal wall opposite the opening in the outer wall and extending around the outer wall opposite the opening in the inner wall.

11. A silo having a symmetrical outer wall made up of hollow blocks rectangular in cross section and laid in horizontal courses with even horizontal mortar beds between the courses, an inner chordal wall bonding with the outer wall, an entrance opening through the outer wall and openings through the inner wall, flat perforated sheets of metal imbedded in the mortar beds and overlapping at their ends to form a continuous circumferential reinforcement, such reinforcement connecting entirely around the structure in the outer wall except at said door, the reinforcement being formed around the outer wall opposite the opening through the inner wall.

12. A silo structure wherein there is an outer annular wall and an inner wall, both walls being constructed of hollow blocks laid on horizontal mortar beds, said beds lying in common planes and having a reinforcement comprised of overlapping grid like metal sheets.

13. A silo structure wherein there is an outer circular wall and an inner straight wall bonded into the outer wall and dividing the inside of the structure into two compartments, one of said compartments comprising a silage chamber and having an elongated door opening communicating with the other compartment.

14. A silo structure wherein there is an outer circular wall and an inner wall formed of hollow tile and dividing the interior of the structure into a silage chamber and chute chamber, the outer wall having a door opening at the base thereof and communicating with the chute chamber and the inner wall having an elongated door opening forming communication between the two chambers, the mortar beds of both walls lying beneath the inner door opening being interbonded and reinforced by grid like metal sheets.

15. A silo structure having an outer circular wall composed of rectangular tile laid on reinforced horizontal mortar beds, the continuity of the lower courses being broken by a door opening; an inner wall dividing the interior of the structure into two chambers and having the continuity of the upper courses broken by an elongated door opening, and transverse walls interbonded with said inner and outer walls and positioned adjacent the door openings.

16. A silo construction consisting of a symmetrical outer wall and an inner chordal wall connected therewith, there being a door opening through the outer wall and a filling opening through the inner wall, the former being positioned lower than the lat-

ter and a circumferential reinforcement for the silo extending across the chordal wall but below the opening in the inner wall and extending around the outer wall but above 5 the opening in the outer wall.

17. A silo having a symmetrical outer wall made up of hollow blocks rectangular in cross section, laid in horizontal courses with even horizontal mortar beds between the 10 courses, an inner hollow chordal wall bonding with the outer wall, an entrance open-

ing through the outer wall and openings through the inner wall, flat perforated sheets of metal imbedded in the mortar beds and overlapping at their ends to form a 15 continuous circumferential reinforcement, such reinforcement passing through the inner wall where the outer wall is broken by said door.

In testimony whereof, I hereunto affix 20 my signature.

FREDERICK HEATH.
